(57) **CLAIM**

The ornamental design for a light fixture, as shown and described.

DESCRIPTION

FIG. 1 is a perspective view of the light fixture showing my new design;

FIG. 2 front elevational view thereof, the rear view being a mirror image;

FIG. 3 is a bottom plan view thereof;

FIG. 4 is a right side elevational view, the left side being a mirror image; and,

FIG. 5 is a top plan view thereof.

The broken lines shown on the drawings are for illustrative purposes only and form no part of the claimed design.
